UNITED STATES PATENT OFFICE.

LEANDER J. KNISELEY AND WILLIAM B. KNISELEY, OF BURNSVILLE, WEST VIRGINIA.

DOOR-HANGER.

1,267,556.

Specification of Letters Patent.

Patented May 28, 1918.

Application filed July 7, 1914. Serial No. 849,585.

To all whom it may concern:

Be it known that we, LEANDER J. KNISELEY and WILLIAM B. KNISELEY, citizens of the United States, residing at Burnsville, in the county of Braxton, State of West Virginia, have invented certain new and useful Improvements in Door-Hangers; and we do hereby declare the following to be a full, clear, and exact description of the invention, 10 such as will enable others skilled in the art to which it appertains to make and use the same.

This invention relates to improvements in sliding car doors.

15 One object is to provide a sliding car door and hanger of such construction and arrangement that the door is less liable to be forced out of alinement than doors heretofore, especially under the strain of a load 20 within the car.

A still further object is to provide a sliding car door mounting which will be protected against injury and permit the free working of the parts.

25 Other objects and advantages will be apparent from the following description, when taken in connection with the accompanying drawings.

In the drawings:

30 Figure 1 is an elevation of a portion of a side of a car and my improved door.

Fig. 2 is an enlarged vertical detail sectional view on the line 2—2 of Fig. 1, the intermediate portion of the door and car 35 side being broken away.

Fig. 3 is an enlarged vertical section on the line 3—3 of Fig. 1.

Fig. 4 is a horizontal section on the line 4—4 of Fig. 1.

40 Referring particularly to the accompanying drawings, 10 represents a portion of the side of a car which is provided with the usual doorway opening. Disposed vertically adjacent one edge of the door is a batten 11 which acts as a stop to limit the 45 door in its closing movement. Secured at a proper distance from the opposite side of the doorway is a similar batten 12 for limiting the opening movement of the door.

50 Disposed respectively above and below the doorway and having its ends passing through the ends of the battens and secured to the wall of the car are the rails 13 and 14, these rails being supported intermediate

their ends by the brackets 15 secured to the 55 wall of the car. A door 16 is disposed to move across the doorway, this door being provided with the hangers 17 in the upper edge provided with grooved rollers 18 engaging on the upper track. Secured to the 60 lower edge of the door, are the strap hangers 19 which carry grooved rollers 20 engaging with the lower track. These lower hangers extend around below the lower rail so as to prevent the rollers from leaving the 65 lower track. Secured at its opposite ends to the lower ends of the battens or stops is a guard rail 21 disposed outwardly of the lower rail for the purpose of protecting the 70 lower rail from damage by contact with the other objects. It will be noted that the lower edge of the door is provided with recesses 22 in which the rollers of the lower hangers are seated thus obviating the necessity of placing the lower track too far below the doorway, the track being arranged 75 approximately even with the sill of the doorway or a few inches therebelow. The door is provided with a suitable handle 23 by means of which the same may be moved back 80 and forth along the tracks. The door is also provided with a suitable lock 24.

From the foregoing it will thus be seen that by reason of the fact that the door is supported on rollers both at the top and 85 bottom insures that the same will be held in proper position in front of the doorway, and by reason of the fact that the lower hangers embrace the lower track, the lower edge of the door cannot move outwardly out 90 of engagement therewith. Attention is particularly called to the middle supports for the tracks which prevent any sagging thereof so that the door will at all times move smoothly and evenly into open and 95 closed position. The guard rail protects the lower track and lower hanger of the door so that injury to the lower track is prevented.

What is claimed is:—

In a car door construction, the combination of a door body having recesses formed upwardly from its lower edge between the front and rear sides of the body, rollers mounted in said recesses, said rollers being 105 carried upon journals which project through the door body, a rail supporting said rollers, U-shaped brackets having arms embracing

100

105

the outer sides of the wall of said recesses and bridging over the latter and also said rail, said roller journals also passing through said arms and being fastened 5 therein, and connecting bolts passing entirely through the arms of the brackets and the door body.

In testimony whereof we affix our signatures in the presence of two witnesses.

LEANDER J. KNISELEY.
